UNITED STATES PATENT OFFICE.

DAVID M. Haight, OF OSWEGO, ILLINOIS.

DESIGN FOR AN EGG-TESTER.

SPECIFICATION forming part of Design No. 29,942, dated January 3, 1899.

Application filed December 5, 1898. Serial No. 698,378. Term of patent 14 years.

To all whom it may concern:

- Be it known that I, DAVID M. HAIGHT, of Oswego, in the county of Kendall, and in the State of Illinois, have invented and produced 5 a certain new and original Design for an Egg-Tester; and I do hereby declare that the following is a full, clear, and exact description thereof, reference being had to the accompanying drawings, in which—
- 10 Figure 1 is a perspective view of an egg-tester embodying my design, and Fig. 2 is a horizontal section thereof.
- Letters of like name and kind refer to like parts in each of the figures.
- 15 The object of my invention is to provide a new and original shape for egg-testers; and to this end said invention consists in the design for an egg-tester, substantially as hereinafter set forth.

The essential feature of my design consists 20 in the shape of the egg-tester A, which in horizontal section is semicylindrical or substantially semicylindrical. In the flat side, or the one opposite the curved side, there are two holes B and B, while in the top is a hole 25 C, which is partially surrounded by a bent plate D.

Having thus described my invention, what I claim is—

The design for an egg-tester, substantially 30 as herein shown and described.

In testimony that I claim the foregoing I have hereunto set my hand this 12th day of November, A. D. 1898.

DAVID M. HAIGHT.
